PULL OR THE LIKE

La Verne E. Clayton, Rockford, Ill., assignor to Amerock Corporation, Rockford, Ill., a corporation of Illinois

Original design application May 4, 1964, Ser. No. 79,811.
Divided and this application June 30, 1965, Ser. No.
86,698

Term of patent 14 years

(Cl. D10—8)

FIG. 1 is a front elevational view of a pull incorporating my new design.

FIG. 2 is a top view of the pull.

FIG. 3 is a side view of the pull as viewed from the left in FIG. 1.

FIG. 4 is a sectional view taken along the line 4—4 in FIG. 1.

The design is particularly characterized by a margin of elongated, flat-faced beads with rounded inner ends and an inner circle of spherical beads separated from the marginal beads by a concave annular ring.

This application is a division of my copending application Serial No. D. 79,811, filed May 4, 1964.

I claim:

The design for a pull or the like, substantially as shown and described.
